UNITED STATES PATENT OFFICE.

HENRY JOHNSON, OF DUDLEY, ENGLAND.

LOOKOUT-GLASS FOR LOCOMOTIVES, &c.

SPECIFICATION forming part of Letters Patent No. 625,398, dated May 23, 1899.

Application filed December 28, 1897. Serial No. 663,967. (No model.)

To all whom it may concern:

Be it known that I, HENRY JOHNSON, a subject of Her Majesty the Queen of Great Britain and Ireland, residing at Dudley, in the county of Worcester, England, have invented certain new and useful Improvements in Lookout-Glasses for Locomotives, Steamboats, Lighthouses, and other Lookout Purposes, (for which I have obtained a patent in Great Britain, No. 2,047, bearing date January 29, 1895,) of which the following is a specification.

My invention has for its object so to construct and arrange the parts of lookout-glasses as to afford means for warming the said glasses, whereby snow is prevented from accumulating on or is immediately dislodged or melted from the weather side of the glasses and a clear lookout thus obtained for the engine-driver or person during falls of snow or snowstorms. The same object—namely, the dislodging of the snow from the lookout-glass—may also be effected by the other arrangement hereinafter described.

My improved lookout-glasses are particularly applicable to locomotives, and I will describe my invention as applied to a locomotive.

A lookout-glass constructed according to one of the arrangements of my invention consists, essentially, of two metallic circular or other frames placed edge to edge, each frame supporting a circular or other pane of glass, the two parallel panes of glass forming between them a steam-tight chamber. One of the said frames is fixed to the weather-shield of the locomotive by snugs and screw-bolts, and the other or outer frame is hinged at one side to the inner or fixed frame, so that the outer or movable frame can be opened from or closed upon the inner fixed frame on the weather-shield after the manner of a clock-face frame. When the outer movable frame is closed upon the fixed inner frame, the two frames are secured together at the bottom by thumb-screws. The panes of glass are inserted in grooves or recesses, lined or packed with india-rubber, made in the inner faces of the two frames, and each pane is fixed in its groove or recess by a fixing metallic ring secured by set-screws to the outside edge of each frame. By means of a packing-ring between each of the outside fixed rings and the

lined or packed recesses or grooves in which the panes are fitted the said panes are securely fixed in their places and rendered steam-tight by the securing of the said rings. In the bottom of the supporting-frames two passages are made, opening into the steam-tight chamber formed between the two panes of the lookout-glass. By one of these passages dry steam is conducted to the chamber and by the other passage exhaust-steam or water of condensation is removed from the said chamber. By means of the steam-heated chamber between the two parallel panes the said panes are so heated that any snow accumulating on the weather side of the glass is immediately dislodged or melted.

Figure 1 of the accompanying drawings represents in front elevation and Fig. 2 in vertical section, taken on the line A B, Fig. 1, the lookout-glass of a locomotive constructed according to this arrangement of my invention. Fig. 3 is a front elevation, and Fig. 4 a vertical section, of a modified form. Fig. 5 is a front view, and Fig. 6 a section, of still another form; and Figs. 7 and 8 are respectively a front view and section of a still further modification.

The same letters of reference indicate the same parts in all the figures.

a b are the metallic circular frames of the lookout-glass, placed edge to edge, supporting the two parallel panes of glass a² b², the said panes forming between them a steam-tight chamber c. The boiler side of the lookout-glass is marked D, and the foot-plate side is marked E. The metallic inner frame a is fixed to the weather-shield or cab-plate d by lugs and screw-bolts at f' f', and the other or outer metallic frame b is hinged at e to the top (or side) of the fixed inner frame a. In place of the lugs for fixing the glass to the shield a flange may be employed, as seen in the arrangements hereinafter described. Upon the hinge e the outer or movable carrying-frame b can be opened or closed upon the inner fixed frame a after the manner of the bezel of a clock. The two frames a b are secured together by the lugs and screws at f. The panes of glass are inserted in grooves or recesses at g in the two frames a b, and each pane is fixed in its supporting-frame by the outside fixing metallic ring h, secured by

screw-pins i to the principal frame or ring, as seen in the section Fig. 2. Before the panes are placed in the recess g and secured by the rings h the said recesses are packed 5 or lined with the packing-rings of india-rubber, (marked k), so that by the securing of the fixing-rings h the panes are fixed in the recesses of the supporting-frames and rendered steam-tight.

- 10 $l m$ are two pipes or passages at the bottom of the lookout-glass frames $a b$, opening into the steam-tight chamber c between the two panes $a^2 b^2$. By the pipe or passage l dry steam is conducted to the steam-tight chamber c , and by the other pipe or passage m exhaust-steam or water of condensation is removed from the said chamber. A pipe l^2 , fitted into the steam-passage l and provided with a regulator-cock, conveys steam from 15 the locomotive-boiler to the chamber c , and a pipe m^2 , fitted into the exhaust-passage m , provided with a regulator-cock, discharges the water of condensation.

By supplying steam to the chamber c , between the parallel panes of glass $a^2 b^2$, the said panes are maintained at such a temperature that in case of a snowstorm the snow is immediately dislodged or melted from or prevented from accumulating on the weather side of the 20 lookout-glass and a clear lookout for the engine-driver obtained. By unfastening and opening the outer or movable pane-carrying frame b access may be obtained to the inside faces of the two panes $a^2 b^2$ for cleaning them.

25 Instead of the heating-chamber formed between the two parallel panes of the lookout-glass directly—that is, by admitting dry steam into the said chamber—it may be heated by a circular tube or coil of copper or by an annular channel at the circumferential part of the chamber, through which tube or coil or channel dry steam is made to circulate. In these cases the metallic frames of the panes of glass are modified either to receive the heating 30 tube or coil or have formed in them the annular channel. The said metallic frames may also be constructed as to permit of both frames being opened toward the driver.

One of the last-described modifications of 35 the lookout-glass is represented in front elevation in Fig. 3 and vertical section in Fig. 4. In this modified lookout-glass the outer frame is marked b and the inner frame a , and the parallel panes of glass carried by them b^2 40 a^2 . The inside frame a is formed with a circumferential or annular recess p for receiving the circular copper tube or coil q by which the air-tight chamber c , between the two panes $a^2 b^2$, is heated. The lower ends of the heating tube or coil q within the chamber c are 45 connected to steam-passages $q^2 q^3$ in the lower part of the inner frame a , a small hole (see dotted lines in Fig. 3) being made between the said steam-passages $q^2 q^3$ and opening into 50 the chamber c to serve as an outlet for moisture from the said chamber. The steam-pas-

55 sages $q^2 q^3$ are connected with the boiler by the pipes $q^4 q^5$, (provided with stop-cocks,) whereby steam is made to circulate through the circular pipe or coil q , the radiated heat 60 from which heats the chamber c and the panes $a^2 b^2$, the outer pane, or that exposed to the weather, being maintained at a sufficiently high temperature to melt or dislodge snow or frost from it. By fixing a steam-cock to each 65 of the steam-pipes q^4 and q^5 a complete circulation of steam through the pipe or coil q may be obtained, and by shutting both cocks the pipe or coil may be rendered steamless during summer or when the heating apparatus 70 is not required to be used. By the use of a third cock and blow-off pipe and opening the same and closing one of the steam-cocks described steam may be blown through the coil into the atmosphere for cleansing the said 75 coil. In this arrangement the pane-carrying frame b is jointed or hinged at e to the pane-carrying frame a and is fastened by the pin or bolt e^2 . $h h$ are the metallic fixing-rings 80 of the panes, and $i i$ the fixing-pins.

85 Instead of fitting a copper tube or coil in the circumferential recess of the lookout-glass frame, as last described and illustrated, the copper tube or coil may be replaced by making in the circumferential part of the frame an 90 annular steam heating-passage. This modification is represented in front elevation in Fig. 5 and vertical section in Fig. 6, where the annular steam heating-passage formed in the circumferential part of the frame is marked 95 r . In this arrangement both of the pane-carrying frames $a b$ are capable of opening toward the driver—that is, the inner frame a is hinged at a^3 near the recessed part of the said frame a and is fastened at the bottom by 100 the pin or bolt a^4 . Similarly the outer frame b is hinged at b^3 and is fastened at the bottom by the pin or bolt b^4 . It will be seen that the frame b is made sufficiently large to admit of the frame a being lifted through the opening 105 made to receive the said frame b , thereby affording the means of cleaning both sides of both panes from the foot-plate of the locomotive. The inner pane a^2 is secured to its frame by the fixing metal ring h and outer metal 110 rim t , and the outer pane b^2 is secured to its frame by the metal ring h^2 , as seen in the sectional view Fig. 6. In order that the hinged frames may be properly spaced from each other, distance-pins s are provided, and thus 115 in closing the outer frame b these pins will arrest the frame b at the proper point for the ready entry of the securing-pin b^4 . The distance-pins also prevent warping of the frames 120 toward each other. The pins s are threaded 125 into the frame b and bear at their opposite extremities against the frame a . The other parts of this lookout-glass do not differ in construction from those of the arrangements 130 Figs. 3 and 4.

Fig. 7 represents in elevation, and Fig. 8 in vertical section, another modification in which

the double-hinged arrangement of the frames is represented in combination with a copper heating tube or coil of the kind shown in Figs. 3 and 4.

5 Although I have described and represented my invention in connection with lookout-glasses having a circular figure, yet I wish it to be understood that my improvements may be applied to lookout-glasses having other 10 figures—such, for example, as square or oblong lookout-glasses.

The several arrangements described and represented of the lookout-glasses for locomotives are also applicable to steamboats, 15 lighthouses, and for other purposes where lookout-glasses are required.

What I claim as my invention, and desire to secure by Letters Patent, is—

1. A lookout-glass for locomotives having 20 double pane - carrying frames one of said frames being hinged for permitting access to the inside faces of the said panes for cleaning them substantially as hereinbefore described

and illustrated in the accompanying drawings. 25

2. In a lookout-glass for locomotives, a pair of parallel pane-carrying frames, one of said frames being hinged for permitting access to the inner sides of said panes, and means for heating the space between said panes, sub- 30

stantially as described. 3. In a lookout-glass for locomotives, the combination with the window-casing of a pair of parallel pane-carrying frames of different size hinged thereto and opening in the same 35 direction and a channel for heating fluid contained in the casing outside the limits of the smaller hinged frame, substantially as described.

In witness whereof I have hereunto set my 40 hand in presence of two witnesses.

HENRY JOHNSON.
